PAGE 2

FIGURE 1 is a front perspective view of the convertible automobile embodying my design;

FIGURE 2 is a rear perspective view thereof;

FIGURE 3 is a side view of the convertible automobile with the top open; and

FIGURE 4 is a rear perspective view thereof with the top completely down.

The broken lines represent portions of the automobile visible through the windshield and side windows. The undisclosed side of the automobile is a mirror image of the side shown.

I claim:

The ornamental design for a convertible automobile, as shown and described.
